UNITED STATES PATENT OFFICE.

ERVIN S. MUMMERT, OF HANOVER, PENNSYLVANIA, ASSIGNOR TO MUMMERT-DIXON COMPANY, OF HANOVER, PENNSYLVANIA, A CORPORATION OF PENNSYLVANIA.

WIRE LOOM.

Application filed August 17, 1923. Serial No. 657,926.

- This invention relates to looms, and more especially to looms for the weaving of fabrics of wire strands, such as window and door screens, and while the present application is drawn to a machine for the production of such fabrics, I wish it understood that the improvements herein disclosed are applicable to machines for producing fabrics of different kinds of material and of different size mesh to be used for other purposes, such, for instance, as heavier wire screens for the separation of sand, gravel, seeds, etc., or to produce fabrics formed of fibrous strands, such as cotton screening, etc.
- One object is to provide means, in such a machine, whereby the maximum uniformity of spacing between the weft or filler wires or threads is obtained by the timed co-operative action of the heddles, the shuttle transferring bars and the reed to place the weft wires at the lay of the completed fabric in exact spaced intervals during the constant, uniform, longitudinal movement of the warp wires or threads.
- Another object is to provide tensioning means for automatically exerting a constant and uniform strain or tension on the warp wires while permitting the alternate up and down movement of the same, through the action of the heddle frames, with a minimum danger of breakage of said wires, said means serving also to provide compensating means to intermittently drive the take-up roll for the completed fabric, since the effective diameter of the roll of fabric is ever increasing and the woven fabric is fed forward at a regular rate of speed, the take up of said fabric is done at intervals, after a predetermined amount of excess has been woven the automatic compensating means being then automatically re-set for continued weaving of the fabric.
- A further object is to provide means in a loom of this character, for easily and quickly changing certain gears to provide for the necessary rate of speed of travel of the warp wires in weaving different kinds and different size mesh fabrics.
- A still further object is to provide means for accurately alining the shuttle transfer bars in exact longitudinal alinement with each other and transversely of the machine, so that the said shuttle may be readily re-
- leased by one bar and received by the other during its transit through the shed formed by the warp wires, in their alternate up and down movement through the action of the heddle frames, which in the present invention are positively driven by cranks and pitmen and caused to uniformly travel in rigid guides in the frame of the machine.
- A still further object is to provide means for enabling the operator to manually operate the take-up mechanism when it is desired to wind up some of said excess fabric on the take-up roll or to unwind the same as when an inspection is necessary and also to provide means for manually shifting the drive belt from the loose pulley to the drive pulley or vice versa.
- A final object is to provide means for automatically stopping the action of the loom by the shifting of the drive belt from a drive pulley to a loose pulley, in the event one or more of the strand or warp wires breaks (as when the loom is engaged in weaving wire fabric), said belt being readily shifted again back to the drive pulley by the hand of the operator, when the said wire or wires have been again joined together and the weaving operation is continued.
- A full and complete understanding of the invention may be obtained from a consideration of the following detailed description, taken in connection with the accompanying drawings forming a part of this specification; it being understood that while the drawings show a practical form of the invention, the latter is not to be confined to strict conformity with the showing thereof, but may be changed or modified, so long as such changes or modifications mark no material departure from the salient features of the invention, as specifically pointed out in the appended claims.
- In the drawings, in which similar reference characters designate corresponding parts throughout the several figures:
- Figure 1 is a side elevation of the right hand side of the improved loom.
- Figure 2 is a side elevation of the left hand side of the same.
- Figure 3 is a front elevation thereof.
- Figure 4 is an elevation of the inside of the left hand frame member.
- Figure 5 is an enlarged longitudinal sec-

tional view through the sectional, power-transmitting shaft for intermittently driving the take-up roll.

Figure 6 is an enlarged view in elevation 5 of the automatic means for tensioning the fabric and causing the intermittent action of the winding roll.

Figure 7 is an elevation, on a similar scale, of the subject matter of figure 6, and 10 taken at right angles thereto, or as viewed from the front of the machine.

Figure 8 is a vertical section taken on the line 8—8 of Figure 7 and looking in the direction of the arrows.

15 Figure 9 is a similar view taken on the line 9—9 of Figure 6 and looking in the direction of the arrows.

Figure 18 is a detail sectional view, taken on the line 18—18 of Figure 15 and drawn on an enlarged scale.

45 Figure 19 is an enlarged detail side elevation of a portion of the machine frame and showing the automatic stop mechanism applied thereto for throwing the loom out of operation when one or more of the strand 50 or warp wires breaks.

Figure 20 is an elevation of the subject matter of Figure 19 as viewed from the rear of the machine.

55 Figure 21 is a top plan view of the same. Figure 22 is a detail sectional view taken on the line 22—22 of Figure 21 and looking in the direction of the arrows.

Figure 23 is a view similar to Figure 22 and showing the belt-shifter latch, after 60 being tripped.

Figure 24 is a detail perspective view of the belt shifting fork.

65 Figure 25 is a detail perspective view of the sliding locking member for engaging the belt-shifter latch for maintaining the

drive belt in proper position on the drive pulley.

Figure 26 is a detail perspective view of the bracket for supporting the belt shifting mechanism. 70

Figure 27 is a detail perspective view of the belt-shifter latch.

Figure 28 is a diagrammatic showing of the method of wiring for the operation of the belt shifting mechanism. 75

Figure 29 is an elevation of the strand or warp wire drum on which the bare wires are initially wrapped before threading the same through the loom.

Figure 30 is a transverse sectional view 80 through the same.

The machine comprises a right and a left hand frame member, 1 and 2, respectively, formed of suitable cast metal and similar in construction, as to the main features, each member comprising a lower, longitudinal sill 3 arranged horizontally and in spaced relation to the floor or support, an intermediate, horizontal sill 4 and a top, horizontal sill 5, said sills being joined together by a vertical front post or standard 6, an intermediate vertical standard 7, extending above the top sill 5, as at 7^a, and a rear vertical standard 8, the several sills and posts being preferably formed integrally and provided with the usual marginal strengthening beads or flanges generally used in such structures. 90

The lower ends of the several posts extend below the lower sill and are provided with outstanding feet for bolting the machine frame to the floor, and the two frame members are spaced apart a distance to accommodate the maximum width of fabric to be woven, suitable tie rods being connected to the said members to rigidly maintain the same in proper spaced and parallel relation to each other, such tie rods being located at convenient points where the same will not interfere with the operation of the component parts of the loom. 100

Each rear standard 8 of the frame members 1 and 2 is provided with a seat 9 for the reception of a bearing bracket 10, which is suitably bolted thereto and is adapted to receive the adjacent end of a drum shaft 11, the said shaft being rotatably held in said bearings by detachable bearing caps 12, which may be easily and quickly removed in order to lift the shaft from the supporting brackets. 110

Mounted on the shaft 11 is a strand wire or warp wire drum 13 comprising end heads or spiders 14 of wheel-like formation, and so located and secured to the shaft as to lie immediately within the side frames 1 and 2 and adjacent to the inner faces of the same. The spiders 14 have peripheral rims 15 formed in a plurality of flat faces for the reception of wooden planks 16, whose outer faces are formed in the arc of a circle, and 120

which, when suitably secured to said rims form a complete, circular drum around the outer surface of which is secured a cylinder 17 of sheet metal to form a hard, smooth 5 surface about which the said strand wires are wrapped.

Adjacent to each end, the drum 13 is provided with a series of longitudinally alined 10 apertures or sockets 18 formed through the sheet metal cylinder and the planks, and around the drums are placed a pair of flanged rings 19 having an internal diameter to freely slide thereon, and which are held in adjusted relation to the ends of the drum, 15 and in proper spaced relation to each other, by means of screws or bolts 20, which may be screwed into any pair of diametrically opposite apertures 18 to hold the rings 19 in such adjusted position as to confine the strand 20 wires therebetween in suitable numbers to accord with the width of the fabric being woven, all of which may be readily understood by reference to Figures 29 and 30.

The spider 14 located at the right hand 25 side of the machine has its spokes extended radially beyond the drum 13 and carry an integral spur gear wheel 21, of relatively large diameter, which meshes, at all times, with a relatively small pinion 22 located 30 within the frame and carried by a stud shaft 23 mounted in a suitable bearing formed in the inclined frame bar 24 which connects the intermediate, horizontal sill 4 to the top horizontal sill 5 in the right hand frame 35 member 1.

Mounted on the stud shaft 23, and adjacent to the outer face of the inclined frame bar 24, is a worm wheel 25 of larger diameter than the pinion 22, the worm wheel 40 and the pinion being each keyed or otherwise secured to the stud shaft 23, so that when power is imparted to the said worm wheel, the pinion is consequently rotated to impart a relatively slow rotary motion to the drum 45 13 by reason of the great difference in the diameters of the meshing gears.

The worm wheel 25 is actuated by a worm 50 26 located beneath the same, and mounted on a longitudinally disposed drive shaft 27 located on the outer side of the right hand frame member 1, and having its rear end portion mounted in spaced bearings 28 located at the ends of the worm 26 and suitably bolted to the intermediate, horizontal 55 sill 4, adjacent to the rear end thereof, said bearings preferably having their removable caps formed integrally with an oil pan 29, which surrounds the lower half of the worm 26 and is adapted to be filled with oil, in 60 which said worm revolves for the purpose of lubricating the connection between the worm and the worm wheel. (Refer to Figures 1 and 5.)

The forward end of the shaft 27 extends 65 through and beyond a bearing 30 secured to

the frame member 1 at the intersection of the intermediate sill 4 and the intermediate standard 7, so that the said shaft has three points of support in the spaced bearings 28 and the front bearing 30 and spacing collars 70 31 mounted on the shaft at the ends of the worm 26, which is keyed to said shaft, and between the said bearings 28, serve to prevent any longitudinal movement of the main drive shaft 27 in its several bearings. 75

The shaft 27 carries a spline 32 at a point intermediate of the front bearing 28 and the bearing 30, and interlocked with said spline and mounted on the shaft 27 is a slideable bevelled pinion 33 adapted to be thrown into and out of mesh with another bevelled pinion 34, which is carried by and adapted to rotate with a stud shaft 35 suitably mounted in a bearing in the intermediate, horizontal sill 4, and at right angles to the drive shaft 85 27.

At the inner side of the sill 4, the stud shaft 35 carries an interchangeable spur gear 36 which is adapted to receive power from an adjustable idler gear 37 for imparting motion to the drum 13 through the bevelled pinions 34 and 33, the shaft 27, worm 26, worm wheel 25, spur pinion 22 and spur gear 21. 90

The adjustable idler gear 37 is rotatably mounted at the lower end of a depending arm 38 of a bell-crank lever, which is fulcrumed at its elbow portion upon a transverse shaft 39 which extends entirely across the machine, and has its end portions mounted in suitable bearings in the upper portions of the inclined frame bars 24 in each of the frame members 1 and 2, the said shaft being adapted to revolve in its bearings independently of the said bell crank lever having the depending arm 38. (Figures 1, 10 and 11.) 105

The other arm 40 of the bell crank extends forwardly and overlaps the intermediate standard 7 at the right hand side of the machine, and is provided at its free forward end with an arcuate shaped head 41 having a longitudinally disposed, arcuate slot 42 formed on the arc of a circle, having its center at the axis of the supporting shaft 39, and adapted to receive a binding bolt 43 screwed into the inner face of the intermediate standard 7 of the right hand frame member 1 to hold the bell crank lever in any desired adjustment for a purpose to be explained. 115

Mounted on and keyed or otherwise secured to the shaft 39 is a spur pinion 44 which meshes with and is adapted to drive the pinion 37, and these two pinions are preferably of substantially the same diameter while the interchangeable pinion 36 may be of different sizes according to the size and kind of mesh being imparted to the woven fabric, as for instance, when it 125 130

is desired to decrease the speed of the drum 13, as when weaving a finer mesh, at which time the strand or warp wires must be fed more slowly, the spur gear 36 may be removed from the stud shaft 35, and a larger spur gear wheel 36^a (as illustrated in Figure 10 of the drawings) may be substituted therefor, which will result in a slower rotary movement of said drum 13. In order 10 to make such change, the binding bolt 43 must be loosened and the bell crank lever rocked upwardly about its fulcrum on the shaft 39, at which time the adjustable idler gear 37, which will remain in mesh with the gear 44, may be suitably meshed with the teeth of the larger wheel 36^a. By a similar operation the gear 36 may be replaced by a smaller gear for increasing the speed of rotation of the drum 13, at which time the bell crank lever will be lowered, as will be readily understood.

The shaft 39 extends beyond the bearing formed in the inclined frame bar 24 at each side of the machine, and where extending 25 through the frame member 2 at the left hand side, a drive gear 45 is mounted which, as shown in Figure 2 of the drawings, is in mesh with another gear wheel 46 of considerably smaller diameter, and carried on the 30 projecting end portion of another transverse shaft 47 arranged directly over the shaft 39 and mounted in bearings secured to the upper surface of the longitudinal upper sills 5 of each frame member.

Outside of the sill 5 of the right hand frame member 1, the shaft 47 carries a gear wheel 48, which is of the same diameter as the wheel 45, and which, in turn, meshes with a relatively small idler gear wheel 49 35 adjustably mounted in an upward extension of the right hand frame member 1, and which meshes with another spur pinion, constituting a drive pinion 50 secured to a drive pulley 51 and mounted on a stud shaft 45 52, there being a loose pulley 53 immediately adjacent to said drive pulley.

The idler 49 is rotatably mounted on an adjustable stud 53^a, which is held in adjusted position by a binding nut 53^b in an 50 arcuate slot 54 formed in the aforesaid upward extension 55 of the right hand frame member. The slot 54 is formed on the arc of a circle whose center is the axis of the shaft 47, so that the ratio of the drive gear 55 wheel 50 and the idler 49 may be changed and the meshing connection still maintained to produce the required timing of the drum 13. The stud shaft 52 is also suitably mounted in the upper portion of the upward extension 55, and suitable provision made to render the same rigid and strong to withstand the strain of the drive belt 56.

When, as is sometimes necessary, it is desired to stop the rotation of the drum 13 65 without shifting the belt and stopping the

operation of the entire machine, a foot pedal 57 located at the forward end of the right hand frame member is located in position to be pressed by the right foot of the operator, (Figure 1) said pedal being normally elevated and extending back along the side of the machine frame where it is fulcrumed at an intermediate point upon a pivot post 58, the rearwardly extending portion of the pedal carrying a weight 59, 70 which maintains the foot portion of the pedal in elevated position. An upstanding arm 60 is formed integrally with the pedal bar, and is bent outwardly for connection to a pull rod 61, which extends rearwardly and upwardly, the rear end of the same being in turn pivotally connected to the intermediate portion of a shifting yoke arm 62, whose lower end is fulcrumed upon an outstanding pin or bolt 63 mounted at 75 the lower edge of the lower sill 3 of the right hand frame member, and substantially beneath the slidable, bevelled pinion 33. The shifting yoke arm 62 is provided at its upper end with a yoke 64, having 80 inwardly directed, opposed pins fitting into an annular groove 65 formed in the hub of the bevelled pinion 33, so that when the pedal 57 is depressed, the said bevelled pinion 33 is forced forwardly along the spline 90 32 of the shaft 27 (Figures 1 and 5) and since the said pinion meshes with the co-acting pinion 34 at the front portion thereof, the connection between the two pinions is broken, and the train of gearing between 95 the pinion 34 and the drum 13 remain inactive. When the foot of the operator is removed from the pedal 57, the weight 59 immediately throws the said pinions into mesh again, for a continuation of the drive 100 of the drum 13.

Since the strand or warp wires are continually rolling off the drum 13 during the operation of the machine and the same are threaded through the various working parts of the loom in a manner to be later described, some provision must be made to take up the woven fabric and to maintain the said wires in a taut condition, such means including 115 means for allowing a portion of the said fabric to be woven and, while still maintained in a taut condition, to accumulate to a certain amount before being wound on the final take-up roll. The latter feature compensates for the ever-increasing diameter of 120 the roll of completed fabric.

In order to accomplish this desired result, there is provided a front extension shaft 66 mounted at the right hand side of the machine and in exact longitudinal alinement with the shaft 27, (Figure 5) the same being mounted in spaced bearings 67—67 secured to the frame member 1 adjacent to the front end thereof and preferably formed integral- 125 ly, as in the case of the rear bearings 28, and 130

provided with the same kind of a pan 68 for containing a quantity of oil, in which there is adapted to revolve a worm 69 secured to the shaft 66, and spaced from the bearings 5 67 by collars 70, which prevent any longitudinal movement of the shaft 66 through said bearings.

The rear end of the shaft 66 abuts against the front end of the main shaft 27, and is 10 adapted to be intermittently rotated in unison therewith by means of a toothed clutch member 71, keyed or otherwise secured to the rear or abutting end of the front shaft 66, and into which there is adapted to be slid a 15 corresponding clutch collar or member 72 having interfitting teeth for the purpose, and provided with an annular groove 73 for the reception of inwardly directed, opposed pins of a shifting yoke 74 pivotally mounted, 20 at its lower end, upon a pin 75 secured in the upper end of an upstanding post 76, preferably formed integrally on the upper edge of the lower sill 3 in advance of the intermediate standard 7.

25 When the shifting yoke 74 is rocked in a forward direction, by means yet to be described, the clutch member or collar 72, which is caused to rotate with the shaft 27 by means of a spline 77, is forced into meshing relation with the clutch member 71 and power is transmitted to the shaft 66, which causes the rotation of the worm 69, and the latter, which is in mesh with a relatively large worm wheel 78 located over the same 30 35 and mounted on a drum shaft 79, in turn causes the latter to rotate whenever the aforesaid clutch members are in engagement.

The drum shaft 79 extends entirely across the machine and is mounted in suitable bearings 40 80 secured to each frame member 1 and 2, and said shaft is provided with a drum 81 constituting the take-up drum for retrieving the woven fabric as the same comes from the tensioning device about to be described, 45 the said shaft, together with the take-up drum 81 being readily removable from the bearings 80 when the said drum has had a full roll of the completed fabric wound thereon and an empty drum may then be placed in position for further operations. 50 (Figures 8 and 9.)

55 As the take-up drum 81 is designed to be rotated at intervals corresponding to the length of time it takes to weave a predetermined length or amount of fabric, in order that the said amount may be rolled or wound upon the same, which has an ever increasing diameter, some means must be provided for automatically throwing the clutch members 60 71 and 72 into connection to cause the drum to take up the fabric and in like manner, to throw out the clutch to stop the winding action of the drum when the said amount of fabric has been taken up, during all of which

time, the fabric must be maintained in a taut 65 condition.

This is accomplished by means of a tension roll 82 located transversely between the front standards 6 of the frame members and around which a depending, loop portion of 70 the woven fabric is passed beneath the same and then passed upwardly and over the take up drum 81, so that the said roll 82, which is adapted to move up and down, keeps the aforesaid excess amount of woven fabric 75 taut, as the same is being woven and taken from the lay of the loom, and as it is being wound upon the drum 81. Reference is made especially to Figures 6, 7, 8 and 9.

The tension roll 82 is rotatably mounted at 80 its ends in vertically-movable brackets or frames 83 having flaring lower portions provided with ledges or supports 84 for a plurality of weights 85, preferably formed of cast iron and provided with end extensions 85 86 to rest upon said ledges 84, the purpose of the separate weights being to enable the proper amount of tension to be exerted upon the fabric, as more or less weights may be employed. 90

The brackets or frames 83 are each provided with upstanding arms 87 suitably apertured for the reception of a transverse gear shaft 88, extending across the machine and projecting beyond the said arms for the reception of gear wheels 89, located at the inner faces of the front standards 6 and adapted to mesh with racks 90, which are suitably secured to the inner edges of said front standards. As the tension roll moves 100 upwardly and downwardly, the gears at each end thereof cause a uniform movement, and the tension roll is maintained in an exact horizontal position at all times with the result that every strand or warp wire in the 105 woven fabric and beyond the lay of the loom receives an equal amount of pull or tension.

In order to steady the vertical movement of the tension roll, together with the end brackets 83 and the weights 85, and to prevent any lateral or longitudinal play of the same, the trunnions 91 of the roll are extended through the bearing portion of the brackets 83, at each end, and there carry rollers 92 which contact with the vertical side flanges 93 formed on the inner faces of the front standards 6 of each frame member to provide tracks therefor, and to cause the entire tensioning device to move upwardly and downwardly in a smooth manner. 110 115 120

As shown in Figures 6, 7 and 9, the bracket or frame 83 at the right hand side of the machine is provided with a trunnion 94, the inner portion of which is round in cross section and adapted to receive a roller 95, which also traverses the tracks or flanges 93, and the outer portion of said trunnion, which is preferably square in cross section, is extended 125

and projects through a vertical slot 96 formed in the front standard 6 of the right hand frame member 1.

A latch lever 97 is pivoted, at its lower end, 5 on a stud 98 outstanding from the lower portion of the outer face of the right hand, front standard 6, and said latch lever is extended upwardly and formed into a handle 99 to be grasped by the hand of the operator when 10 it is desired to operate the latch lever manually, as will be later described.

The latch lever is located in front of the projecting trunnion 94, and the lower portion of the same is widened transversely of 15 the machine and provided on its rear face, adjacent to the outside of the frame member 1, with a rearwardly directed, inclined cam track 100, normally lying beneath the projecting end of the trunnion 94, and adapted 20 to be engaged by the latter, when the tension device is lowered, to cause a forward movement of the latch lever 97 about its pivot 98.

Between the handle 99 and the widened lower portion of the latch lever 97, a slot, 101 25 is formed, and through said slot the front terminal portion of a clutch operating lever 102 is extended, said lever 102 extending rearwardly in a substantially horizontal position, and having its rear end directed inwardly and rigidly connected to a forwardly extending arm 103 forming a part of the aforesaid shifting yoke 74, which actuates the clutch members 71 and 72 for intermittently driving the take-up drum 81. (Figures 1 and 6.)

The slot 101 is of sufficient height or extent to permit the clutch operating lever 102 to move up and down therein to fully engage or disengage the said clutch members, and 40 located adjacent to the upper end of said slot, the latch lever 97 is provided on its rear face with a rearwardly directed lug 104, whose upper face is perpendicular to the latch lever or in a substantially horizontal 45 plane, while the lower face of said lug is forwardly bevelled and normally lies partially across the aforesaid slot 96 in the frame member. (Figures 6 and 7.)

The clutch operating lever 102 is provided 50 with an outstanding pin 105 square in cross section and lying in the path of and normally resting upon the lug 104 of the latch lever, so that the clutch operating lever 102 will maintain the clutch members 71 and 72 55 in disengagement, and in order to make such engagement of the lug 104 and pin 105 positive, a coiled spring 106 has connection at one end to a pin 107 carried by the lever 102, and at the other end to a pin 108 outstanding 60 from the latch lever 97, said spring being in an inclined position and tending to hold the lever 102 downwardly and the latch lever 97 rearwardly.

Secured to the clutch operating lever 102 65 in rear of the latch lever 97, is an upstanding

arm 109 having an inturned nose 110 at its upper end, which lies directly opposite the aforesaid slot 96 at the upper end of the latter and in the path of movement of the extended trunnion 94 of the tensioning device. (Figures 6 and 7.)

The trunnion 94 is apertured adjacent to its outer end and a vertically disposed pin 111 is slidably mounted in the same for relative vertical movement therein, the upper end of the said pin extending somewhat above the trunnion and having an enlarged head 112 at its upper end, while the lower end carries a stop washer 113 held by a suitable pin to prevent the pin from being forced upwardly out of the aperture by a coiled, expansion spring 114 surrounding said pin and bearing respectively against the enlarged head and the extended trunnion. In addition to the spring pressed pin 111, the trunnion 94 also carries a rigidly mounted, upstanding pin or post 115, the function of which, as well as the purpose and operation of all of these associated parts will soon become apparent. (Figures 6 and 7.)

The intermediate standards 7 of each frame member 1 and 2 is extended upwardly above the top sills 5 and suitably formed for the attachment of the lower ends of upstanding supports 116, which are preferably formed of channel iron and extend above the tops of the frame members, a distance substantially equal to the heights of said frame, the said supports being in perfect alignment transversely of the machine and having their intermediate portions joined together by a suitable frame 117 to brace the same and prevent any relative lateral movement thereof. (Figures 1 and 3.) The upper ends of the standards 116 are bent forwardly into goose necks 118, the forwardly extending terminals of which are apertured for the reception of a pivot rod 119, the extending terminals of which are adapted to receive the upper ends of swinging hanger arms 120, preferably formed of suitable cast metal and provided with marginal strengthening flanges to render the same stiff and rigid.

The lower ends of the hangers 120 extend somewhat below the top surfaces of the top sills 5 and are adjacent to the outer faces of the same, said hangers having forwardly extending brackets 121 provided with vertically disposed bearing eyes, in which are mounted the spindles of horizontally disposed rollers 122, which are adapted to roll against the outer flat surfaces of arcuate tracks 123 set into the upper arcuate surfaces of the top horizontal sills 5 where extending between the intermediate standards 7 and the front standards 6. As the swinging hangers 120 are actuated by means about to be described, the rollers 122 will traverse the arcuate tracks 123, which are

formed on the arc of a circle having the axis of the pivot rod 119 as a center, and prevent any lateral movement thereof during the backward and forward movement of 5 the same, said hangers being connected together near their upper ends by a channel iron member 124 and near their lower ends by spaced angle irons 125 which serve to rigidly hold the two hangers together. 10 (Figure 3.).

Mounted on the extended terminals of the shaft 47, which as before stated, extends across the machine from frame to frame, are crank arms 126 counterbalanced by 15 weights 126^a and which are disposed at the same radial point relative to the axis of the shaft, and the said crank arms are connected to the lower ends of the opposite hanger arms 120, by means of pitmen 127 20 so that, as the train of gearing is actuated, during the operation of the loom, the said hangers are caused to partake of a constant swinging motion to carry the lay of the loom backwardly and forwardly to allow 25 the traverse of the shuttle through the shed of the warp wires and to pack the transverse filler or weft wires at the proper, pre-determined distance apart.

The upper portions of the hanger arms 30 120, which partake of only a slight amount of swinging motion, are provided on their front surfaces with suitable bearings 128, adjacent to the pivot rod 119, for the reception of the outer ends of spaced shafts 35 129 which are in exact longitudinal alignment with each other, the inner ends of the same being mounted in spaced bearings 130, (see Figure 3) and extending through the same a sufficient distance for the reception 40 of inner grooved pulleys 131 which are also spaced somewhat apart.

The outer ends of the separate shafts 129 extend beyond the said bearings 128, where 45 they are provided with other grooved pulleys 132, all of said pulleys being securely keyed or otherwise fastened to the shafts 129 and constituting driving means for the shuttle actuating bars, as will be explained.

The outer grooved pulleys 132 are connected by chain lengths 133 to the hooked, 50 upper ends of inclined rods 134 which extend downwardly and rearwardly where they are connected, by adjustable means 135, to the ends of crank arms 136 mounted on the 55 projecting terminals of the aforesaid shaft 39 which extends across the machine. The crank arms 136 are disposed diametrically opposite to each other on the shaft 39, so that the rotation of the latter causes alternate pulls on the two rods and chains at opposite sides of the machine. (Figures 1 and 3.)

The connecting channel iron 124 near the tops of the hangers 120 is connected by a 60 vertically-disposed, centrally located plate

137, which has its lower end secured to the upper transverse angle iron 125, and mounted on said plate at an intermediate point between the transverse connecting irons 124 and 125, is a double grooved pulley 138, one 70 half of which is located in front of the plate and the other half in the rear thereof and joined together so as to rotate in unison in either direction. (Figures 1, 3, 16 and 17.)

The pulleys 138 are connected by short lengths of chain 139 to the aforesaid pulleys 131, the grooves of which are located directly above the peripheries of the grooves in the pulleys 138, as clearly shown in Figure 80 3 of the drawings. The chains 139 are wrapped around the pulleys 131 in the same direction, that is, they each fall from the front sides thereof, and the lower ends of said chains are oppositely wrapped about the 85 pulleys 138 at opposite sides of the supporting plate 137, so that, as one crank arm 136 exerts a pull upon its connected chain 133, the separate shaft 129 actuated thereby will be rotated in one direction, while the opposite separate shaft 129 will be correspondingly rotated in an opposite direction through the medium of the pull of the chain 139 connected thereto, and the action of the double 90 grooved pulley 138, and when the opposite crank arm 136 pulls its respective chain 133, the opposite movement is imparted to said parts, the wheel 138 travelling substantially three-fourths of a revolution in each direction.

For the reason that the chains 139 fall from the grooved pulleys 131 in alignment with each other transversely of the machine, the double grooved pulleys 138 must necessarily be arranged as close together as possible, in order that said chains may properly be seated in the grooves of the latter pulleys which are rotated on an axis at right angles to the upper pulleys, and this necessitates the use of a relatively thin support in the form of the plate 137. In order to provide ample bearing for the pulleys 138, which would otherwise soon become loose in the bearing under the strain of the alternate 100 pulls of the chains, etc., it is necessary to provide a specially formed bearing in the said supporting plate, as shown in Figures 15 to 18 inclusive, and described as follows.

The upstanding plate 137 is provided with a round aperture 140, through which there is passed a bushing 141 having an integral outstanding annular flange 142 at one end. This flange abuts against the plate 137 and receives an annular locking ring 143 at the other end, said ring bearing against the opposite side of the plate held in position by rivets 144 passing through alined apertures in the flange, the plate and the ring respectively, as clearly shown in Figure 18.

One of the grooved pulleys 138 is provided

with a central, circular recess 145 for the reception of the flanged end of the bushing 142, while the other grooved pulley 138 is provided with an annular recess 146 to receive the other end of said bushing together with the retaining ring 143, and the same pulley is further provided with a central, round projection 147 which enters into the recess 145 of the other pulley and abuts 5 against the wall thereof, the two pulleys being held together by screws or bolts 148. By this means, the pulleys are provided with a relatively broad bearing surface upon a relatively thin support, and the strain exerted by the pull of the chains 139 will not cause any wobbling motion to said pulleys.

The pulleys 138 are provided, upon their outer faces, with oppositely disposed crank arms 149, having their outer ends provided 10 with a longitudinal series of apertures 150 for the adjustable connection of pull rods 151, which extend outwardly, transversely of the machine, and considerably beyond the sides of the same, where they are connected 15 as at 152 (Figure 3) to shuttle transfer bars 153 which are adapted to be moved, longitudinally thereby through adjustable bearing blocks 154 carried by the ends of the angle irons 125 which extend considerably beyond 20 the sides of the machine frames 1 and 2.

The transfer bars 153 are provided at their inner ends with shuttle holding members 155, which are adapted to receive and release the shuttle 156 (as shown in Figure 35 12), upon being actuated by the lever 157, when the same contacts with the shoe 158 at the outer end of the lowermost angle iron 125 and at the finish of the inward movement of the transfer bar 153 through the 40 pull of the rod 151, but since this particular mechanism forms no part of the present invention, no detailed description of the same will be given. It will be seen, however, that by reason of the particular arrangement of 45 the actuating mechanism for the transfer bars, the latter will be simultaneously drawn together, towards the center of the machine, where the transfer of the shuttle is made, and that the said bars are immediately 50 caused to separate, moving in opposite directions, one of the holding members 155 carrying the shuttle on to the completion of the traverse, thus stretching the weft wire, transversely of the machine, alternately in 55 opposite directions, to form the filler of the fabric. By reason of the regular advance of the fabric, through the steady feed of the warp wires from the drum 13, at the rear end of the machine, and the steady take up 60 of the woven fabric, through the steady feed of the warp wires from the drum 13, at the rear end of the machine, and the steady take up of the woven fabric by the weighted roller 82 and the intermittent action 65 of the take-up drum 81, at the front end

of the machine, the said weft wires, placed by the shuttle, are caused to assume regular spaced relation to each other, while in perfect parallel alinement. Said relation may be made to agree or not agree with the spaced 70 relation of the warp wires as may be desired, depending upon the timing of the various parts through the various means for adjustment, as will be readily understood.

This transit of the shuttle through the 75 shed of the warp wires takes place when the hanger arms 120 are in their rearmost position, where they are brought by the simultaneous rearward movement of the cranks 126 and the pitmen 127, as shown in Figure 80 2 of the drawings, the shuttle being then quickly carried by one of the transfer bars to the center of the machine, when the trip lever 157 on each bar 153, by contacting with the shoe 158, causes the opening of the 85 holder 155, when the initial impetus of the shuttle 156 carries the same to the opposite holder 155, which instantly starts to recede, through the action of the crank arms 149, thus receiving, grasping and carrying the 90 shuttle on to the end of the stroke.

As the finish of said stroke is made, the cranks 126 and pitmen 127 start forward carrying the hangers 120 and the lay of the 95 loom therewith, and forcing the said weft wire to its proper spaced, position at the fell of the fabric, said wire being carried forward by the usual reed wires 159 supported by reed holding strips 160 secured in the front 100 open sides of the angle irons 125, as indicated in Figure 3.

In Figures 12, 13 and 14 there is illustrated the means for alining the shuttle transfer rods 153, so that the holders 155 may be accurately advanced towards each other for transferring the shuttle. The bearing blocks 154 comprise a back plate 161, which is held in position between the angle irons 125 and at the outer ends of the same, by means of bolts 162 passing through upper 105 and lower flanges of said plate, and adjacent to each end, the latter is provided with vertically disposed slots 163. Tap screws 164 are passed through these slots from the rear, and have their forward threaded ends screwed into an adjustable guide plate 165, which is provided with a central, longitudinal projecting portion having an angular bearing seat 166 extending throughout its 110 length and forming two sides of a square, one being the bottom and horizontal and the other a vertical side. A cap or cover plate 167 is applied to the projecting portion of the guide plate, said cap having a longitudinally-disposed, angular recess or bearing seat 168 extending throughout its length and forming the other two sides of a square, that is the top and the other side thereof, said cap being held in its mounted position by 115 means of bolts or screws 169. The bearing 120 seat 168 is provided with a central, longitudinal 125 recess or bearing seat 170 extending throughout its length and forming the other two sides of a square, that is the top and the other side thereof, said cap being held in its mounted position by 130 means of bolts or screws 171. The bearing

formed by the recesses 166 and 168 provides a relatively long bearing for the shuttle transfer rods 153, and it will be seen that by properly adjusting the screws 164 in the 5 slots 163, the said bearing may be made to align perfectly with the opposite bearing.

When it is desired to turn the drum 13 by hand, in either direction, as is often the case when threading the warp wires A through 10 the machine, or when a wire breaks and it is necessary to allow a little slack for splicing the same, the bevelled pinion 33 is moved forwardly on the shaft 27 to unmesh the same from the bevelled pinion 34, by 15 depressing the foot pedal 57, thus breaking the train of gears from the drive belt 56. A crank 170 located at the upper portion of the right hand front standard 6, (Figure 1) is then grasped by the hand of the operator 20 and turned to rotate a short shaft 171, mounted in a bearing 172 on the side of the frame member 1. This short shaft, through a knuckle joint 173, in turn, rotates an inclined shaft 174, having its lower end supported in an angularly disposed bearing 175, and carrying at its lower projecting end a bevelled pinion 176 which meshes with a bevelled gear wheel 177 carried by the horizontal shaft 27. The bevelled gear wheel 30 177, which is mounted adjacent to the bearing 30 is provided in its hub portion with an annular groove 177^a, into which there projects the inturned terminal of a clip plate 177^b which is bolted to said bearing 30, thus 35 preventing any longitudinal movement of the wheel relative to the shaft and at the same time permitting the said shaft to rotate independently of the wheel 177. The shaft 27 is thus rotated in either direction 40 as desired, assuming that the pedal 57 is still depressed and that the clutch members 71 and 72 are disengaged.

When the pinion 33 is thus held forward, the socket 178 (see Figure 5) formed in the 45 extension of the hub beyond the annular groove 65 in which the shifting yoke 64 operates, is moved forwardly into surrounding relation to the toothed clutch member 179, formed on the rearwardly extending hub of 50 the bevelled gear wheel 177, the said socket 178 having complementary teeth for engagement therewith. It will thus be seen that cutting out the power-driven train of gears throws the hand operated driving means 55 into connection with the driving shaft 27 for rotating the drum 13 in either direction to allow of correction or mending of the strand or warp wires or the woven fabric at the front end of the machine.

60 It is also sometimes desirable to turn the take-up drum in one or the other direction, independently of the other parts of the loom and independently of the power driven gearing, and for this purpose the following 65 means has been provided.

The take up drum shaft 79 is extended at the right hand side of the machine somewhat beyond the hub of the worm wheel 78, which latter is provided with clutch teeth 180, which are normally in mesh with complementary teeth 181 formed in the inner hub portion of a hand wheel 182 (see Figures 7 and 9), and the said hand wheel is slidably mounted on the extended shaft 79 by means of a spline 183, having an enlarged 70 head for preventing the hand wheel from sliding off of the shaft when moved outwardly by the hand of the operator to break the connection between the teeth 180 and 181. When such connection is broken, the 75 hand wheel may be used to turn the drum shaft 79 and also the drum 81 in either direction without disturbing the rest of the gearing, as the worm wheel 78 is loosely mounted on the said shaft and may exert a 80 rotary movement thereto, under power, only when the hand wheel 182 is at its inner position to mesh the teeth.

At the rear end of the machine, the standards 8 are continued upwardly and are provided on their rear faces with alined cradle bearings 184 which are adapted to receive end trunnions 185 of a rear idler roll 186, extending entirely across the machine and located over the drum 13. (Figure 2.) In 90 front of the roll 186, the said upward extensions are provided with vertical slots 187 for properly adjusting substantially horizontal arms 188, having horizontally alined 95 openings to receive the ends of guiding and separating bars 189, which also extend across the machine and are supported in spaced relation by said arms 188, which terminate at their forward ends in rectangular frames 100 105 190.

At their front ends, the side frame members 1 and 2 are also extended upwardly and formed into alined cradle bearings 191, for the reception of end trunnions 192 of a front idler roll 193, which also extends entirely 110 across the machine, and whose front face is substantially over the front face of the aforesaid tension roll 82, there being an unobstructed passage between the two rolls. 115 (Figure 2.)

The inner faces of the upward extensions 7^a of the intermediate standards 7, at each side of the machine, are provided with vertically disposed, spaced grooves 7^b (Figure 4) for the reception of the usual heddle 120 frames 194, but since the same may be of any desired construction, no attempt has been made to illustrate them in detail. These frames are adapted to be alternately moved up and down in their respective grooves by 125 means of pitmen 195, as best shown in Figure 2 of the drawings, said pitmen deriving their power from oppositely disposed crank arms 196, arranged just within the frame members 1 and 2, at each side of the ma- 130

chine, and mounted on a transverse shaft 197, extending entirely across the machine, and having its ends supported in bearings in the intermediate standards 7, somewhat 5 above the lower sills 3.

One crank arm 196 extends towards the front of the machine while the other extends towards the rear thereof, and the pitmen 195 are connected to the same as well as to 10 the heddle frames 194 near their ends by threaded connectors 198 which permit the effective lengths of said pitmen to be increased or decreased as may be found necessary to give the proper amount of lift to the 15 heddle frames.

The shaft 197 is provided at a point adjacent to the left hand frame member 2, with a forwardly extending operating crank arm 199, having a longitudinally adjustable 20 wrist-pin block 200 (Figure 2), and connected to this wrist pin is a drive pitman 201, the upper end of which is connected to a substantially horizontal operating lever 202, located at the inner side of the frame 25 member 2 and having its rear end pivotally mounted, for up and down rocking motion, upon a pivot pin 203 carried by the inclined portion 24 of the left hand frame member 2.

Mounted on the transverse shaft 39 and at 30 the inner side of the operating lever 202 is a wheel 204 having in its face adjacent to said lever, an eccentric groove 205 for the reception of a roller 206, mounted on a horizontal pin projecting from the inner face of the 35 lever 202 and located directly below the shaft 39. As the said shaft revolves through the medium of the gearing at the other side of the machine, it will be seen that the eccentric groove in wheel 204 will cause an 40 alternate up and down movement to the heddle frames.

Located at each side of the machine, just 45 within the frame members 1 and 2 and directly over the take-up drum 81, there is secured, as by bolts, a vertically disposed plate 207, having at its vertical front and rear edges ribs or flanges to form a vertical guide or runway for a solid, round bar or roller 209, which has its ends projected into said 50 guides or runways and is adapted to lie upon and to move upwardly as the diameter of the roll of fabric upon the take-up drum is increased, the said roller serving to wrap the roll uniformly.

55 When the drum, with the warp wires A previously wrapped in proper manner and position thereon, has been placed in the bearings 10 at the rear of the machine and the cap members 12 secured in place over the 60 trunnions thereof, the ends of said warp wires are first carried forwardly and upwardly and over the idler roll 186. Every alternate wire is then passed beneath the first separating bar 189, and then over the 65 second bar 189, while the other alternate

wires are passed over the first bar and under the second, the alternate wires crossing each other between the two bars. From this point all of the wires are passed forwardly in parallel relation to and through the eyes (not 70 shown) in the heddle frames 194, and then

on through the reed wires 159 carried by the angle irons 125 at the lower end of the swinging frame supported by the hangers 120. The wires are then passed over the 75

front idler roll 193, thence downwardly in front of and beneath the tension roll 82 and then upwardly in rear of the same, where they are secured to the take up roll 81; the 80

said tension roll being initially in an elevated position within its runways. When the 85 loom is thus threaded or set for operation, power is applied to the drive pulley 51 through the drive belt 56 and the train of

gearing, as described, rotates the drum 13 in a relatively slow and regular manner to uniformly feed off the warp wires A therefrom. At the same time, the heddles 194 are actuated by the cranks and pitmen to guide the 90

wires and to alternately raise and lower the same for the purpose of forming the shed B at the intermediate portion of the machine, in the region of the upstanding supports 116, the same shed B being located in the horizontal 95 plane of the shuttle 156 when the hangers 120 are at their rearmost position adjacent to said hangers. At this instant, the cranks 136 act in unison to cause a transverse movement of the shuttle across the lay of the

loom and through the shed B, whereupon the 100 cranks 126 immediately drive the swinging frame forward to cause the reed 159 to carry the weft wire last placed forwardly, and into spaced relation to the previously placed weft wire, such timing of the parts and 105 spacing of the wires being readily accomplished by the various means of adjustment provided, and by means of the interchangeable speed gear 36 which provides for a faster or a slower motion of the drum 13 and the other actuated parts.

At this time the clutch members 71 and 110 72 are separated by reason of the fact that the lever 102 is held in elevated position by the pin 105 which now rests upon the lug 104, the coiled spring 106 exerting a constant pull to hold the two members in such relation.

Since in the present machine, the finished 115 product must be drawn under tension away from the point of weaving and wrapped or wound upon a drum or roll acting as the pulling or feeding medium and since, in the weaving of cloth or fabrics, the same must be made in relatively great lengths, it follows

that the wound fabric results in an ever increasing diameter of the roll thereof which, since the said roll or drum is rotated at a regular rate of speed, would effect the pull 120 upon the stretch of woven fabric and the

- strand or warp wires. Were this not compensated for, the increasing roll would soon break all the warp wires in the fabric as will be readily understood, and in order to 5 permit of the winding of lengths of fabric on the power driven take-up drum with the resultant increase in the diameter of said roll and without danger to the woven fabric, the following means have been provided.
- 10 As the operation of weaving progresses, the woven fabric C travels down the front end of the machine to form a loop or excess under constant strain by the weighted tension roll 82, which slowly and uniformly 15 falls, with its end brackets or frames 83 guided in the runways in the frame members, and carrying the extended trunnion 94 downwardly through the slot 96, during 20 which time the take-up roll 81 remains stationary.
- When sufficient fabric has been woven and maintained in a taut condition by the falling tension device, and the trunnion 94 has reached a position in the lower portion of the 25 slot 96 and begins to contact with the inclined upper or rear surface of the rearwardly directed cam track 100, the co-acting parts, up to this point, remain in their initial positions, as there is nothing to interfere 30 with the downward movement of the tensioning device. The weight of the tensioning device now begins to cause a forward swinging movement of the latch lever 97 by reason of the action of the trunnion 94 on 35 the cam track 100, the said weight being sufficient to overcome the pull of the coiled spring 106, which is slowly and gradually stretched, as the tensioning device carrying the weights 35 continues to move downward.
- 40 The continued forward movement of the latch lever, thus caused, finally carries the lug 104 from beneath the outstanding pin 105, when the spring 106, which is now fully stretched or distended, causes a quick and 45 positive downward pull upon the clutch actuating lever 102 to the bottom of the slot 101 in the latch lever as indicated in dotted lines in Figure 6. This movement throws the clutch member 72 forwardly and into 50 meshing relation to the clutch member 71, keyed to the extension shaft 66, whereupon the take-up drum 81 is immediately rotated in a relatively fast manner to wind the woven fabric C thereon through the medium 55 of the worm 69 and the wheel 78, the hand wheel 182 being, at this time in a position to lock the said worm wheel 78 to the drum-shaft 79.
- As the take-up drum is positively driven 60 by the gearing in direct connection with the source of power, the woven fabric C in winding thereon lifts the entire tensioning device including roll, end brackets, weights and the trunnion 94, the said trunnion 94, in rising, 65 rides the inclined edge of the cam track 100 and permits the latch lever 97 to move rearwardly until the same contacts with the outstanding pin 105. In the meantime the pin 105 is being held tightly against the rear edge of the latch lever 97 by the coiled spring 106, and as the said trunnion 94 is being positively raised by the tensioning device, the head 112 of the pin 111 encounters the nose 110 which is directly over the said trunnion, and starts to lift the lever 102 together with the pin 105. The tendency now is for the said pin, in co-action with the bevelled lower edge of the lug 104, to force the latch lever 97 forwardly and to stretch the spring 106, and the resistance 70 thus offered retards the upward movement of the lever 102 and nose 110 and causes a compression of the coiled spring 114 surrounding the pin 111 upstanding from the trunnion 94.
- 75 This compression of the spring 114 continues during the upward movement of the tensioning device, until the upper end of the pin or post 115 which is rigidly mounted on the trunnion 94 engages the aforesaid nose 110, when the aforesaid resistance is overcome and the pin 105 starts to ride the lower inclined edge of the lug 104. At the moment the end of the incline is reached, the spring 114, now under compression, forces the pin 111, the arm 109 and the clutch operating lever 102 upward, with a quick motion, and the clutch members 71 and 72 are separated and the winding operation of the drum 81 immediately ceases. The pin 105 is now immediately forced to take its normal seat upon the lug 104, as the latch lever 97 is drawn rearwardly by the spring 106.
- 80 With the tensioning device again elevated, the winding or take-up drum stationary, and the various members again in their normal positions, the weaving of the fabric, which has continued throughout the aforesaid intermittent winding operation, may continue, 85 the said tensioning device starting immediately to slowly descend until the above described operation takes place again. When it is desired to trip the parts and start the take-up drum to winding by hand, it will be 90 seen that all the operator has to do is to grasp the handle 99 and swing the same towards the front of the machine to break the connection between the pin 105 and lug 104 when operation of throwing in the clutch 95 takes place as before, and when the desired amount of fabric has been wound, the operator may lift the lever 102 to throw out the clutch, by grasping the projecting end of the same where extending through the latch lever 107, whereupon the engagement of the pin 105 and lug 104 will automatically take place 100 to hold the clutch out of engagement.
- 105 During the operation of weaving the fabric it often happens that a weaker strand or 110

warp wire becomes broken, and such breakage may not be detected by the operator until the defective weaving shows up at the front of the machine, if some automatic stop mechanism is not provided in the machine. To overcome this difficulty the following described means has been provided which is illustrated principally in Figures 19 to 28 inclusive, and also shown applied to the loom in Figures 1, 2 and 3 of the drawings.

The stop mechanism is designed to be tripped or actuated electrically when a broken wire occurs, to throw the drive belt from the driving pulley to a loose pulley, when all the moving parts of the machine will come immediately to a stand-still.

Mounted on the rear face of the upright support 116 at the right hand side of the machine, and elevated somewhat above the shaft 52, is a supporting bracket 210 comprising an attaching plate formed integrally therewith and adapted to be bolted to the said support, as shown in detail in Figure 26. This bracket carries an outstanding arm 211 extending transversely of the machine and above and a little in front of the drive pulley 51 and the loose pulley 53, said arm having upper and lower longitudinal flanges 212 to form a guideway.

The bracket 210 also carries a rearwardly extending arm 213 formed integrally with a terminal, inwardly directed arm 214 extending towards the center of the machine and having its inner end turned upwardly and provided with a forwardly extending pivot pin 215. The intermediate, longitudinally disposed arm 213 is provided with an aperture 216, which is adapted to form a sliding bearing for the reception of a belt shifting rod 217 extending transversely of the machine and parallel to the guide arm 211. The right hand end of said rod, where lying over the pulleys, is provided with an adjustable belt-shifting fork 218, having a depending eye 219 for adjustment along the rod and set thereon by a set screw 220. The eye 219 elevates the fork above the supporting and shifting rod 217, and is provided with a forwardly extending tongue 221 which enters the guideway between the flanges 212 of the guide arm 211, so that the rod and fork may be moved longitudinally and the same are prevented from any rocking motion.

Mounted on the shifting rod 217, immediately in rear of the upright support 116, is a locking member 222 (see Figure 25), the same comprising an elongated, metallic block arranged parallel with the rod 217 and spaced above the same by depending eyes 223 carrying set screws 224 for securing the member in adjusted position along the rod. These eyes are secured to the rod with the intermediate arm 213 of the supporting bracket between them, as seen in Figures 20 and 21, so that the rod may partake of longitudinal

movement through the aperture 216 before one of said eyes contacts with said arm to arrest said movement.

Mounted on the pin 215 of the supporting bracket is a latch lever 225 having at its inner end an angular bend terminating in an eye 226 for the reception of the said pin 215, to which it is pivotally secured by a cotter pin, the other or outer end of said latch lever having a terminal finger 227 directed towards the front of the machine, and in a position to overhang and at times to rest upon the upper surface of the locking member 222. The outer end of said member 222 is provided with a depressed seat 228 having an inner inclined wall 229, and the aforesaid finger 227 of the latch lever is correspondingly bevelled at 230 and is adapted to fit down into said seat, the co-acting bevelled walls abutting and normally preventing any relative longitudinal movement of the members 222 and 225.

A depending arm 231 is formed integrally with the latch lever 225 and is connected at its lower end to a contractile spring 232, which has its other, or inner end connected to a collar 233 connected to the shifting rod 217 adjacent to the center of the machine by a set screw 234, which may be loosened to allow the said collar to be set at different positions along the rod to increase or decrease the pull of said spring.

Adjacent to the finger 227, the latch lever is further provided with a rearwardly extending arm 235 having an outstanding pivot pin 236 at the terminal of the same, said pivot pin being at right angles to the arm and adapted to carry a depending, vertically-disposed tripping bar 237, which hangs down between the frame member 1 and the drive gear 50 (see Figure 20), the lower end of said tripping bar extending below the shaft 52 upon which the pulleys and the gear 50 are mounted.

The front edge of the tripping bar is cut away from the lower end to a point above said shaft to provide an inclined shoulder 238 which is adapted, when a broken strand or warp wire occurs, to be drawn forwardly and into the path of a lifting lug 239 in the form of a key set into the inner hub portion of the drive gear 50.

Beneath the guide arm 211 and formed integrally therewith, adjacent to the support 116, is a depending lug 240 having an outstanding pivot pin 241, upon which is mounted a bell-crank lever 242 adapted to move longitudinally of the machine. The bell crank lever has a depending arm 243 pivotally connected at its lower end to a link or pull bar 244 which extends rearwardly, and is in turn pivotally connected to an intermediate point of the tripping bar 237. The forwardly extending, horizontal arm 245 of the bell crank lever is pivotally con-

nected to the lower end of a core 246 which extends up into a solenoid 247 secured to and supported by an insulated plate 248 carried by the supporting bracket 210. The 5 weight of the tripping bar 237 together with the bell crank lever and the core, when the solenoid is not energized, suffices to hold the shoulder 238 out of the path of movement of the lifting lug 239, which moves up- 10 wardly on the rear side by reason of the direction of travel of the pulleys as indicated by the arrows in Figure 19.

With the shifting fork 218 located above the drive pulley 51, which latter is in a position adjacent to the frame of the machine, (refer to Figure 20), the retractile spring 232 is held under tension by parts 227 and 225, as the rod 217 has been moved towards the left hand side of the machine (it being 20 remembered that Figure 20 is a rear elevation) thus carrying the collar 233 therewith, the other end of the said spring being held stationary by the depending arm 231 of the latch lever 225. The latter lever is 25 pivoted on a rigid pin 215 of the stationary supporting bracket 210 which thus holds the spring under tension, the pull of the latter exerting a downward pressure on the latch lever to hold the finger 227 in the seat 228 30 of the locking member 222, with the bevelled surfaces of the latter abutting. The pull of the spring 232 is constantly tending to draw the rod 217 and the shifting fork 218 thereon outwardly, or to the right of the 35 machine, and to shift the belt from the drive pulley 51 to the loose pulley 53, but the finger 227 prevents such movement by its engagement in the seat of the locking member 222 which is held to the rod 217.

40 It thus becomes necessary to lift the said finger 227 from the seat 228 before the spring 232 can shift the fork 218, and to accomplish this result electrically, when one or more of the warp wires A are broken, the 45 rectangular frames 190, hereinbefore mentioned are equipped with blocks 249 of insulating material for supporting the upper and lower strands 250 of a U-shaped contact wire (see Figure 1 also diagram of Figure 28). All of the strand wires A where 50 leaving the front separating bar 189 pass between the said upper and lower strands 250 of the contact wire before they advance to the heddles, and if one or more of said 55 warp wires break, contact is immediately made with either the upper or the lower strand of the contact wire, which is electrically connected by a wire 251 with one of the binding posts 252 carried by the insulating plate 248. The wire 251 is also 60 connected through a wire 253 with a battery 254 and thence back to the solenoid 247. From another of the binding posts 252 which is in connection with the solenoid 65 winding, there leads another wire 255 to a

spring contact 256 carried at the end of a supporting arm 257 formed of wood or other insulating material and secured to an offset portion 210^a of the aforesaid supporting bracket 210. The arm 257 extends inwardly towards the center of the machine and the contact spring 257 is directed rearwardly and in the path of the locking member 222 carried by the rod 217, and is adapted to contact with the inner end of said 70 locking member when the same is in the inner position with the belt shifting fork 218 holding the belt 56 on the inner or drive pulley 51. It will be seen that a complete 75 electrical circuit is broken by the gap between the insulated U-shaped wire 250 and the parts of the machine which acts as a ground by reason of the insulation 249 surrounding the same wire in the rectangular frames 190.

80 When one of the wires A breaks, it contacts with the wire 250 and closes the circuit, through the machine, to the locking member 222, through the spring contact 256, wire 255, to the solenoid winding, thence through wire 253 to battery 254, then to wire 251, to the U-shaped contact wire 250 and through the broken warp wire A to the parts of the machine, or ground 258 (Figure 28). The 85 solenoid immediately becomes energized, drawing the core 246 upwardly, thus swinging the bell-crank lever 242, pulling the link 244 and rocking the tripping bar 237 forwardly to locate the shoulder 238 in the path of the rising lifting lug 239, which is revolving in the direction of the arrows with the drive pulley and gear 50. The tripping bar is forced upwardly, thus rocking the latch lever 225 about its pivot 226, thereby increasing the tension on the pull spring 232 and 90 also raising the finger 227 out of the seat 228 of the locking member 222, whereupon the spring slides the rod 217, together with the fork 218 outwardly and carries the belt 56 from the drive pulley 51 to the loose 95 pulley 53.

100 The contact between the member 222 and the spring contact 256 is now broken, and the solenoid is de-energized so that there will be 105 no danger of burning out any of the electrical connections or exhausting the battery, the contacts being considerably separated by the spring 228.

110 When it is desired to start the machine again, say after the above described operation has taken place, and the broken wire or wires have been properly attended to or 115 when starting the machine at the beginning of a day's operations, it being assumed that the drive belt is on the loose pulley, the operator grasps a hand lever 259 (referring to Figures 2 and 3 of the drawings) conveniently located at the front of the machine and adjacent to the left hand frame member 120 2, and swings said lever to the left. This 125

movement rotates a longitudinal rock shaft 260, suitably mounted in bearings 261 attached to the outside of said frame member, one on the front standard 6 and another on 5 the intermediate standard 7, as shown in Figure 2. The rear end of the rock shaft extends beyond the rear bearing, and is provided with an inwardly directed crank arm 262 which is forced to move upwardly and, 10 through the medium of a link or push bar 263, connected to the inner free end thereof, to rock upwardly a bell crank lever whose inner, horizontal arm 264 is connected to said push bar. The bell crank being pivoted to 15 a longitudinally disposed pivot pin 265, carried by the left hand, upstanding support 116, causes the other vertically disposed arm 266 of the bell crank lever to move outwardly or to the left and the said arm, being connected to the end of the shifting bar 217, 20 draws the latter to the left together with the belt shifting fork 218 which shifts the belt from the loose pulley to the drive pulley. This action places the spring 232 under tension, 25 thus rocking the latch lever 225 downwardly and causing the finger 227 to bear against the upper face of the locking member 222, as the latter is drawn to the left of the machine (or to the right as viewed in 30 Figures 20 and 21), until the seat 228 of the locking member is beneath the said finger 227, and the latter is immediately forced thereinto to hold the belt on the drive pulley and maintain the parts in locked engagement, 35 the bevelled faces 229 of the seat and 230 of the finger, respectively, being at an angle sufficient to prevent the pull of the spring 232 from overcoming their frictional engagement.

40 When, however, it is desired to stop the machine at the end of a day's operations, or for the purpose of inspecting the fabric or the parts of the machine for repair or adjustment, or when installing a new drum 13 of warp wires, it is only necessary for the operator to throw the hand lever 259 to the right which, through the connected parts, results in a movement of the shifting rod 217 to the right, thus releasing the tension on 45 the spring 232, by reason of its inner point of attachment 233 being, as a result, moved towards its outer point of attachment to the depending arm 231 of the latch lever 225. This results in an easing up on the pressure 50 of the finger 227 in the seat 228, and the frictional engagement between the aforesaid bevelled faces 229 and 230 is overcome by said easing up and by the manual power being applied and the latch rises and allows 55 the locking member to slide to the right together with the shifting fork 218. The solenoid is ineffective during either of these hand operations to shift the belt from one pulley to the other, as it takes the broken wire to complete the electrical circuit, and 60

as a consequence the engagement of the tripping bar 237 and the lifting lug 239 is not effected.

From the foregoing it will be seen that a loom has been provided for the weaving of fabrics, especially wire fabrics, such as window and door screens, which is equipped with means for taking care of the fabric from start to finish, the complete series of strand or warp wires, previously wound upon the feed drum, being readily placed in position, and said wires being easily threaded through the machine for action upon by the various component parts thereof. It will be further seen that the operator may quickly and conveniently halt the operation for the inspection of the wires or fabric, throwing out the power drive and maintaining complete manual control if desired, whereas in the power-driven operation of the loom, automatic means have been provided for the take-up and tensioning features necessary in looms of this class and that, in the event of a broken strand, the electro-mechanical stop mechanism will throw the machine out of power and immediately stop the same, thus avoiding the weaving of imperfect fabric and a consequent waste of time and material.

What is claimed is:

1. A loom having an intermittently actuated take-up drum for retrieving the fabric after a given length has been woven, a tensioning device therefor comprising a roll arranged to move upwardly and downwardly between the frames of the loom and resting in the looped length of fabric below and at one side of the take-up drum, means for guiding and steadyng the said roll including trunnions and guiding rollers associated therewith, and means for weightng the same to increase or decrease the tension.

2. A tensioning device for woven fabric located between the take-up drum and the point of weaving, comprising a roll located below and in advance of said drum and substantially parallel with the same, said roll having the fabric passed around the same, said roll having trunnions, end frames having bearings for the said trunnions, rollers mounted on the ends of said trunnions, tracks for guiding the rollers to prevent lateral play of said roll, a shaft mounted parallel with the roll in the end frame, cog wheels mounted on said shaft, and vertical racks meshing with the gears to insure uniform vertical movement.

3. A tensioning device for woven fabric located between the take-up drum and the point of weaving, comprising a roll located below and in advance of said drum and substantially parallel with the same, said roll having the fabric passed around the same, said roll having trunnions, end frames having journals for the said trunnions, rollers

mounted on the ends of said trunnions, tracks for guiding the rollers to prevent lateral play of said roll, and gearing on the end frames for insuring uniform vertical movement to the roll.

4. Means for tensioning strands of a fabric, before being wound on a take-up drum, comprising a roll adapted to rest in a loop of the same in advance of the drum, end frames having bearings and receiving the trunnions of said roll, vertical guides and racks located outside the frames, rollers mounted on the ends of the trunnions and travelling in said guides, upward extensions formed in the end frames, a shaft mounted in the extensions parallel with and above the roll, gear wheels carried by the shaft and meshing with the racks, ledges formed on the end frames, and a plurality of weights adapted to be supported on the ledges to increase the tension of the roll on the strands or fabric to the desired amount.

5. In a loom, a take-up drum, means for turning the drum at intervals, said means including a clutch for connecting or disconnecting it with the power, means for normally holding the clutch out of engagement including a clutch shifting lever, vertically movable supporting frames mounted in the loom frame, a tension roll rotatably mounted in the supporting frames and adapted to rest in and maintain taut a loop of the woven fabric before winding on the drum, a latch lever, and coacting means carried by the latch lever, the clutch shifting lever and one of the tension roll supporting frames to cause the clutch to be automatically thrown in for winding up the fabric when the said loop has been woven a given length.

6. In a loom, a take-up drum, means for turning the drum at intervals, said means including a clutch for connecting or disconnecting it with the power, means for normally holding the clutch out of engagement including a clutch shifting lever, vertically movable supporting frames mounted in the loom frame, a tension roll rotatably mounted in the supporting frames and adapted to rest in and maintain taut a loop of the woven fabric before winding on the drum, a latch lever, means carried by the latch lever for supporting the clutch shifting lever to hold the clutch out and the winding drum stationary, said latch lever being capable of manual operation to release the said shifting lever to throw the clutch in for winding the drum at will.

7. In a loom, a take-up drum, means for turning the drum at intervals, said means including a clutch for connecting or disconnecting it with the power, means for normally holding the clutch out of engagement including a clutch shifting lever, vertically movable supporting frames mounted in the loom frame, a tension roll rotatably mounted

in the supporting frames and adapted to rest in and maintain taut a loop of the woven fabric before winding on the drum, a latch lever, a lug mounted on the latch lever, a right angularly disposed lug carried by the shifting lever and normally resting on the first named lug to hold the shifting lever elevated and the clutch out, and a coiled spring connecting the two levers to maintain such engagement until the latch lever is moved to disengage the lugs.

8. In a loom, a fabric winding drum, a power shaft, a separate shaft alined therewith, gearing carried by the latter for turning the drum, and a clutch member carried by the same, a slideable clutch member carried by the drive shaft, a shifting lever connected to the slideable member, a latch lever normally supporting the shifting lever to hold the clutch out, a vertically movable tension roll carrying means for engagement with the latch lever, when said roll is in a lowered position, to disengage the latch lever from the shifting lever, and means for then moving the latter to shift the slideable clutch member to connect the alined shafts for turning the drum.

9. In a loom, a fabric winding drum, normally stationary driving gearing connected to said drum, a gravity actuated tension roll adapted to rest in a loop of the fabric between the lay of the loom and said drum, a shifting lever normally holding the said gearing out of connection with the source of power, a latch lever normally holding said shifting lever in said position, and means controlled directly by the tension roll to engage and trip the latch to allow the shifting lever to connect the drum to the source of power when the loom has woven sufficient fabric in the loop to allow said roll to gravitate to a given point.

10. In a loom, a fabric winding drum, means for rotating said drum, a power shaft, a horizontally disposed shifting lever for normally holding the rotating means disconnected from the power shaft, an upstanding rockable latch lever located adjacent to the free end of the shifting lever and having a lug and a cam face, an outstanding pin carried by the shifting lever and adapted to normally rest on said lug to hold the said turning means out of connection with the power shaft, a coiled spring connecting the latch lever to the shifting lever to maintain said engagement, said latch being manually rockable to release the shifting lever under the pull of the spring to connect the drum with the power shaft.

11. In a loom, a fabric winding drum, means for rotating said drum, a power shaft, a horizontally disposed shifting lever for normally holding the rotating means disconnected from the power shaft, an upstanding, rockable latch lever located adjacent to

- the free end of the shifting lever and having a lug and a cam face, an outstanding pin carried by the shifting lever and adapted to normally rest on said lug to hold the said 5 turning means out of connection with the power shaft, a coiled spring connecting the latch lever to the shifting lever, a tension roll, a weight frame depending from the journals of said roll, an outstanding trunnion 10 projecting from said frame and in the path of the cam on the latch lever, so as to rock the latter to release the shifting lever and to automatically throw the drum into connection with the power shaft when the tension 15 roll is lowered to bring said trunnion into actuating contact with the said cam.
12. In a loom, a fabric winding drum, gearing connecting said drum to a source of power, a clutch included in said gearing, a 20 shifting lever normally holding the clutch out, a latch lever engaging the shifting lever to hold the same in normal position, cam means constructed and arranged to assist in disconnecting the latch lever, a tension roll 25 adapted to be moved up and down by the fabric and having means, when fully descended to rock the latch and release the shifting lever for throwing the said clutch in and to turn the winding drum.
13. In a loom, a fabric winding drum, gearing connecting said drum to a source of power, a clutch included in said gearing, a shifting lever normally holding the clutch 30 out, a latch lever engaging the shifting lever to hold the same in normal position, cam 35 means including a cam face associated with the latch lever to assist in disconnecting it, a tension roll adapted to be moved up and down by the fabric and having means, when 40 fully descended to rock the latch and throw the clutch in to wind the drum, said means carried by the tension roll also acting to lift the shifting lever to automatically throw out 45 said clutch and to stop the winding drum when the roll has been fully elevated by said fabric.
14. In a loom, a fabric winding drum, gearing connecting said drum to a source of power, a clutch included in said gearing, 50 a shifting lever normally holding the clutch out, and having an outstanding pin, a latch lever, a rearwardly directed lug carried by the latch lever and having a bevelled lower ledge, said lug normally supporting the pin on the shifting lever, a spring for holding 55 the two levers in such engagement, means for automatically rocking the latch lever forward to remove the lug from beneath the pin and allow the spring to throw the shifting lever and the clutch into engagement, and 60 means for automatically elevating the shifting lever to throw out the clutch and cause the pin to ride said bevelled lower edge of the lug and become seated on the latter in normal position by the pull of said spring. 65
15. In a loom, a fabric winding drum, gearing connecting said drum to a source of power, a clutch included in said gearing, a shifting lever normally holding the clutch 70 out and having an outstanding pin, a latch lever, a rearwardly directed lug carried by the latch lever and having a bevelled lower edge, said lug normally supporting the pin on the shifting lever, a spring for holding 75 the two levers in such engagement, a cam formed on the rear of the latch lever and having an inclined upper edge, a vertically movable tension roll mounted within the loom frame, pendent weighted end frames carried by the roll, a trunnion mounted on 80 one of the end frames and extending through said loom frame and above said cam, an upstanding spring cushioned pin mounted in the end of the trunnion, a shorter rigid upstanding pin also carried by the shifting 85 lever and having an inturned nose in overhanging relation to the two pins, whereby, when the tension roll is elevated, the longer pin engages said nose as the spring surrounding the same is compressed by the resistance offered to the said nose due to the 90 passage of the pin on the shifting lever over the bevelled lower edge of the lug on the latch lever at which time the said rigid upstanding pin encounters the nose to forcibly 95 elevate the shifting lever and throwing the clutch out and seating the shifting lever pin on the latch lever lug again by reason of the pull of the spring connecting the two levers. 100

In testimony, that I claim the foregoing as my own, I have hereto affixed my signature.

ERVIN S. MUMMERT.
